UNITED STATES PATENT OFFICE.

WILLIAM C. BUTTNER, OF CHICAGO, ILLINOIS.

BOTTLE CAP.

Application filed June 21, 1922. Serial No. 569,956.

To all whom it may concern:

Be it known that I, WILLIAM C. BUTTNER, a citizen of the United States, residing at Chicago, in the county of Cook and State of Illinois, have invented certain new and useful Improvements in Bottle Caps, of which the following is a description.

My invention relates to improvements in bottle caps and has for an object the production of a valved cap whereby bottled liquid may be charged with a gas after said cap has been placed in position thereon, without the removal of said cap.

The invention has among its other objects the production of a device of the kind described which will be simple, convenient, compact, durable, reliable, efficient and satisfactory for use wherever found applicable.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a side elevation of a cap as applied to a bottle;

Figure 2 is a section taken on the line 2—2 of Figure 1;

Figure 3 is a section taken substantially on the line 3—3 of Figure 1;

Figure 4 is a plan view of the cap as seen from its under side;

Figure 5 is a section illustrating a modified form of cap;

Figure 6 is a section taken substantially on the line 6—6 of Figure 5;

Figure 7 is a section similar to that shown in Figure 5 and having a different or crown form of cap;

Figure 8 is a section similar to that shown in Figure 2 but illustrating a different or crown form of cap.

Figure 9 is a section similar to Fig. 7 showing a slightly different construction; and

Figure 10 is a sectional view taken substantially on the line 10—10 of Fig. 9.

In the drawings, wherein I have illustrated the preferred embodiments of my invention, 1 indicates a bottle or any other

suitable container adapted to have liquids or the like therein. The bottle is adapted to be closed by a cap comprising an outer member 2, having a flat top 3, and flanged over, as at 4. The flanged portion 4 is adapted to encircle the neck of the bottle and resiliently engage it thereat. Circumferentially spaced lugs 5 are formed at the free end of the angular flange 4 and extend radially inwardly thereof so as to engage the threads 6 formed on the bottle and hold the cap in place thereat. The top of the cap is provided with a port or opening 7 therethrough, preferably centrally thereof, and through which the liquid contained in the bottle may be charged with a gas, in a manner to be hereinafter described.

A sealing member or washer 8, preferably of cork, rubber, or other suitably compressible resilient material, has a central aperture or opening 9 therethrough in registry with the opening 7 through the cap, and also has another aperture 10 therethrough to one side of said central aperture 9, where the member 8 is of rubber, I have found the opening 9 may be omitted if preferred. Between the cap and the washer, there is arranged a valve member 11, preferably of rubber or other suitable resilient, elastic, or flexible material, having an imperforate portion covering the openings 7, 9 and 10, but having an aperture therethrough to one side of said openings.

In order to charge the contents of the bottle, a gas under pressure is applied to the cap, without removing said cap from the bottle, the pressure of the charging gas causing the valve 11 to be pressed inwardly of the bottle at the central portion thereof, whereby said gas will enter through the port 7 and through the opening 12 and pass into the bottle through the opening 10. As soon as the liquid in the bottle has been sufficiently charged with gas, the gas pressure is released and the pressure within the bottle is sufficient to press the washer and valve upwardly to close the port 7 and maintain it closed thus effectually sealing the bottle.

In the form shown in Figures 5 and 6 the cap 13 is similar to that shown in Figure 2 except that it has a central depressed portion 14 with the port 7 therethrough. The washer 8, having ports 9 and 10, arranged as previously described, contacts directly with the under side of the cap except at the recessed portion 14. In the recessed portion

14 there is arranged an elastic valve member 15 having no apertures whatsoever therethrough and closing the registering port 7 and port 9 is provided, but of such a diameter that it does not close the port 10. Thus it is seen that the recess 14 holds the valve 15 in a predetermined position between the cap and washer. When the bottle is charged, the pressure of the inflowing gas will cause 10 the valve and washer to be pressed inwardly permitting said inflowing gas to pass through port 7 and between the valve and cap into the bottle through the aperture 10. As soon as the gas pressure is released the 15 pressure within the bottle will cause the washer and valve to be pressed upwardly into their normal position, as shown in Figure 5, effectually shutting off the passage of gas outwardly of the bottle.

20 In the form shown in Figure 7, the cap parts are identical with those shown in Figure 5 except that the outer member 16 is crimped about its annular flange 17, in the well known manner of crown caps in order 25 to fit bottles adapted to receive such crown caps.

Figure 8 illustrates another form of the device similar to that shown in Figure 2, except that in this case, as in that illustrated 30 in Figure 7, the external flanged member 18 is crimped to fit a bottle adapted to receive a crown cap.

In the construction shown in Figs. 9 and 35 10, 16 represents the crown cap adapted to be gripped on the bottle 1 in the usual manner, the cap and valve member 15 being similar to that shown in Fig. 7. However, the washer 19, which is preferably of cork, instead of having holes similar to holes 9 40 and 10, is provided with a slit 20. When the gas is discharged into the bottle in the manner previously described, it will enter through the opening 7, pass by the valve and through the slit 20 into the bottle. The 45 pressure of the gas, however, when the charging apparatus is disconnected, will maintain the valve 15 tightly in place and prevent the escape of gas and at the same time this pressure exerted against the washer 50 19 may have a tendency to press the washer so that the slit is more or less closed. There is, therefore, a very effective sealing, and in case the bottle is laid down, the liquid against the cork will cause the same to swell 55 to a slight extent and the bottle will be even more efficiently sealed. It is immaterial as to how the cap is secured on the bottle or container. Generally this is the preferred form of the device, although in so far as 60 service is concerned, they are all effective for the service intended.

In all the forms of devices illustrated, it will be seen that there is provided a valved cap having means whereby a charging gas 65 may be directed into the contents of the bot-

tle after said bottle has been capped, said cap having means for automatically closing the inlet opening therethrough as soon as the charging pressure has been removed. It is a matter of preference as to whether 70 rubber or cork is employed as set forth, and the particular securing means or the manner of securing the device on the bottle, or removing the same may be as desired.

Having thus described my invention, it is obvious that various immaterial modifications may be made in the same without departing from the spirit of my invention; hence I do not wish to be understood as limiting myself to the exact form, arrangement, construction and combination of parts herein shown and described or uses mentioned.

What I claim as new and desire to secure by Letters Patent is

1. A bottle closure constructed to seat on the bottle at the mouth thereof, and provided with a port, and flexible means fixed in position and operable to permit the passage of gas into the bottle through said port and prevent its escape through the port from the bottle.
2. In combination, a bottle cap, a washer disk therein and adapted to engage the rim of the bottle, said cap and washer having apertures therethrough, and a pressure-controlled valve between said cap and washer for controlling the passage of fluid through said apertures.
3. A cap comprising a disk adapted to be positioned over the end of a bottle, a washer within said cap for sealing the rim of the bottle, and self-sealing means between said washer and disk whereby fluid may be admitted into said bottle without removing said cap.
4. A bottle closure comprising a cap having a port, a washer adapted to engage the end of a bottle and having an elongated laterally extending opening therethrough, and an elastic valve disk intermediate said cap and washer for covering said port and extending to adjacent the outer end of said elongated opening, whereby said bottle may be filled with gas through said openings.
5. A bottle closure comprising a cap having a central port, a washer adapted to engage the end of a bottle and having an elongated laterally extending radial opening therethrough, and an elastic valve disk intermediate said cap and washer for covering said port and extending to adjacent the outer end of said elongated opening, whereby said bottle may be filled with gas through said openings.
6. A bottle closure comprising a cap having a central port, a washer adapted to be engaged at its edge between said cap and the end of a bottle and having a radial slit therethrough extending from the center to adjacent its periphery, and an elastic valve

disk between said cap and washer, covering said port and the slit of said washer to only adjacent its outer end, whereby said bottle will be self sealing, but may be 5 charged under pressure through said openings.

7. In combination, a bottle cap, a washer disk therein and adapted to engage the rim of the bottle, said cap and washer having 10 apertures therethrough, and a flexible member between said cap and washer for controlling the passage of fluid through said apertures.

8. In combination, an apertured bottle cap, an apertured washer disk therein and 15 adapted to engage the rim of the bottle, and a flexible member between said cap and washer and imperforate intermediate said apertures for controlling the passage of fluid through said apertures.

20 In testimony whereof, I have hereunto signed my name in the presence of a subscribing witness:

WILLIAM C. BUTTNER.

Witness:

RUTH M. EPHRAIM.
